BUCKLE ATTACHING MACHINE

Jack N. Garrett, McGregor, Tex.

Application July 21, 1955, Serial No. 523,574

10 Claims. (Cl. 140—93)

This invention relates to bagging ties and particularly to a machine for fastening a buckle to one end of a bagging tie.

The principal object of the invention is to provide a machine for automatically attaching a buckle to an end of a length of bagging tie of the kind usually employed for binding cotton bales.

Another object of the invention is to provide a machine including a base, a mounting plate supported perpendicularly on the base, a slotted tie winding shaft supported by said plate for rotative and reciprocative displacement and carrying a pinion, a driving wheel having a sector gear adapted for periodic engagement with said pinion for driving said shaft, a rocker arm connected at one end to said shaft and whose opposite end engages a cam on said wheel for reciprocating said shaft, a buckle drag bar engaging a buckle for positioning the same in relation to a tie wound on said shaft and a hammer and anvil for flattening the convolutions made in said tie by said shaft after the latter is disengaged from said tie.

In the drawings:

Figure 1 is the front elevation of the machine.

Figure 2 is a left side elevational view in which parts are shown in vertical section.

Figure 3 shows the preliminary relative positions of the tie and buckle, and

Figure 4 shows the buckle attached to the tie.

Continuing with a more detailed description of the drawing, reference numeral 10 denotes a base which has a vertical supporting plate 11 to which is attached near the top a main bearing housing 12 by means of a flange 13 on the bearing housing 12 and the bolts 14. Bearing housing 12 holds bearings 15 and 16 into which a driving shaft 17 fits. Shaft 17 has a driving wheel 18 mounted on one end thereof, held in place on shaft 17 by a key 19 which latter is fitted into a keyway in the shaft 17 and a hub 20 on the wheel 18 and by the nut 21 and washer 22. The wheel 18 may be driven by means of a flat belt or fitted with V-grooves for V-belt drive as shown. Fitted tightly on the other end of shaft 17 is a disc-crank 23. The disc-crank 23 has a crank-pin 24 with connecting-rod 25 connected to a plunger 26 by means of a pin 27. The plunger 26 slides in the guide-block 28 and is retained for vertical movement by plate 29 fastened to guide-block 28 by screws 30. The guide-block 30 is held in position by screws 31 fitted into supporting plate 11 with sleeve-spacers 33 extending between the supporting plate 11 and the back of the guide-block 28. An anvil 34 is positioned directly below the guide-block 28 and is fastened to the base 10 by screws 35 through flanges 36 of anvil 34.

A plain bearing-block 37 is mounted on the supporting plate 11 below and through the center line of the bearing housing 12 near the base 10 and is secured by screws 38 through a flange 39 of bearing block 37.

A spindle 40 fits into the bearing block 37, one end of the spindle extending under the guide-block 28. The spindle 40 has two flat parallel sides 41 and a slot 42

2

in its end. A groove 43 is provided in the spindle 40 in which a ball 44 of a retainer 45 rests, the ball being pressed downwardly by a coil spring 46.

A pinion-gear 47 is fitted tight on the spindle 40 behind the supporting plate 11 and is arranged to engage a gear rack or sector 48, mounted as shown inside the rim of the wheel. A ratchet 49 is mounted on the back of the plate 11 to engage the pinion-gear 47 to prevent it from turning clock-wise.

10 There is a collar 50 on spindle 40 immediately behind the pinion-gear 47, having a pin 51 on each side, over which the yoke 52 of a rocker-arm 53 rides. The collar 51 is recessed in the spindle 40 and is retained in place by a collar and screw 54 and 55, respectively.

15 The rocker-arm 53 has a pin 56 extending through a supporting block 57 on each side. The block 57 is fastened to the plate 11 by screws 58 through a flange 59. A spring 60 is attached at one end to the plate 11 and at its opposite end to the rocker-arm 53. A pin 61 extends from the top of rocker-arm 53 on which there is rotatably mounted a roller 62, held in place by nut 63.

A circular cam track 64 is formed on or attached to the inside of the disc 65 of the wheel 18.

20 A plate-cam 66 is attached to the plunger 26 (Figure 1) by the screws 67 with spacer-block 68 between, to clear the plates 29. Near the plate cam 66 is a lever 69, having a grooved wheel 70 mounted on one side thereof, which engages the said plate cam 66. The lever 69 is supported at its top by a pin 71 which passes through the upper end of the lever and the arms of an ear 72 which is welded to an angle-bar 73 extending from the vertical supporting plate 11. The angle-bar 73 is welded to the plate 11 (Figure 2). Of course, other means for joining these parts may be used.

25 A buckle drag bar 74 is connected at one end to the bottom of lever 69 by a pin 75. A grooved wheel 76 is mounted on one side of the drag bar 74 to engage a plate-cam 77, which is secured to the base 10 by means of screws 78 through the flange 79 of the plate-cam 77.

30 In operation:

Figure 1 shows the machine in starting position. A tie 80 (Figure 3) with a buckle 81 slipped over the end is placed with its end in the slot 42 of the spindle 40 with one end of the buckle 81 engaged in a recess 82 (Figure 1) on the free end of the hook-bar 74. The wheel 18 rotates counterclockwise, engaging the gear rack 48 with the pinion gear 47 to revolve the spindle 40 two complete turns. When the spindle 40 has made one and one-half turns, the buckle drag bar 74 moves the buckle 81 from one side of the spindle along with the tie as the spindle 40 completes the second turn, placing the buckle in its final position on the opposite side of the spindle. The retainer 45 now holds the spindle 40 as the gear rack 48 leaves the pinion-gear 47, since the ratchet 49 prevents the spring tension of the wound tie from turning the spindle clockwise.

35 Now, as the wheel 18 continues to turn, the roller 62 on the rocker arm 53 engages the circular cam 64, actuating the rocker arm and causing the spindle 40 to move longitudinally through bearing block 37, withdrawing from the twisted tie, leaving the twisted tie and buckle in position between the anvil 34 and the down moving plunger 26.

40 As the withdrawing action of the spindle 40 is completed, plunger 26 will have traveled downwardly to a position to collapse the rolled tie or band 81 against the anvil 34 into the form shown in Figure 4. As the plunger 26 completes its down-stroke and starts upwardly the completed band is released and removed. When the plunger reaches a point to permit passage of spindle 40, the latter emerges from the bearing 37 to assume its operative or extended position to receive an end of the next

band or tie for a repeat operation. As spindle 40 resumes its extended position, the plunger 26 will have reached its upper position, carrying with it the cam plate 66, permitting the hook-bar 74 to return to its initial position shown in Figure 1:

What is claimed is:

1. In a machine for attaching a buckle to an end of a bagging tie, a base having a vertical support thereon, a horizontally reciprocable and rotatable tie winding spindle in said support having a slotted end to receive an end of said tie having a buckle thereon, a drag bar engageable with one end of said buckle and movable across said spindle to effect interengagement between the opposite end of said buckle and the first convolution of said tie during winding thereof on said spindle, a driving shaft, a driving wheel on said shaft, having a gear sector, a pinion on the opposite end of said spindle with which said gear sector is periodically engaged to rotate said spindle, means pivoted to said support and cooperating with means on said driving wheel for periodically retracting said spindle for the removal of a wound tie and buckle, means for collapsing the convolutions of said tie subsequent to its removal from said spindle, means carried by said driving shaft for actuating said collapsing means and means carried by said collapsing means for actuating said buckle drag bar.

2. In a machine for attaching a buckle to a bagging tie, a base having a vertical support thereon, a spindle mounted horizontally in said support for rotation and longitudinal reciprocation, said spindle having a slotted end for the reception of an end of said tie carrying a buckle, a driving shaft mounted in said support above and parallel with said spindle, a driving wheel on one end of said shaft having a sector gear, a pinion on said spindle with which said sector gear is periodically engageable to rotate said spindle to wind said tie thereon, a drag bar engaging one end of said buckle for transferring the same across said spindle from one side to the other thereof to incorporate the opposite end of said buckle within the convolutions of said tie during winding thereof on said spindle, means actuated by said driving wheel for withdrawing said spindle from the convolutions of said tie, means actuated by said driving shaft for collapsing said convolutions and means carried by said collapsing means for actuating said buckle drag bar.

3. In a machine for attaching a buckle to a bagging tie, a vertical support, a winding spindle rotatably and reciprocably mounted in said support and having a slot in one end thereof for receiving one end of said tie about which said buckle is loosely mounted, a driving shaft mounted in said support above said spindle, a driving wheel mounted on one end of said shaft having means cooperating with means on said spindle for periodically rotating the latter to wind a portion of said tie thereon, a buckled drag bar engaging said buckle and adapted to move the same into a position whereby one end thereof will lie between the first and second convolutions of said tie, means carried jointly by said driving wheel and the opposite end of said spindle for retracting the same to detach the convolutions of said tie from said spindle, an anvil onto which said convolutions are deposited from said spindle, means actuated by said drive shaft to compress said convolutions against said anvil and means carried by said compressing means for actuating said buckle drag bar.

4. In a machine for fastening a buckle to a bagging tie, a rotatable and reciprocable winding spindle to one end of which is attached one end of said tie on which said buckle is loosely mounted adjacent said spindle, a driving shaft and a driving wheel on said shaft, a common support for said driving shaft and spindle, means carried jointly by said driving wheel and said spindle for periodically rotating the latter to wind a portion of said tie thereon, a buckle drag bar adapted to engage a portion of said buckle and dispose another portion thereof in a

position to be embraced by the first convolution made in said tie as said spindle is rotated, means pivoted to said support and to said spindle and actuated in sequence with said periodic rotating means for retracting said spindle from the convolutions of said tie, means actuated by said driving shaft for collapsing the convolutions of said tie to secure said buckle and means carried by said collapsing means for actuating said drag bar in sequence with said periodic rotating means, said retracting means and said collapsing means.

5. In a machine for attaching a buckle to a bagging tie, a rotatable and reciprocable winding spindle having means at one end for the attachment thereto to one end of said bagging tie on which said buckle is loosely mounted, a driving shaft and a driving wheel mounted on said shaft, a common support for said driving shaft and said spindle, a pinion on the opposite end of said spindle, a sector gear carried by said driving wheel for periodic engagement with said pinion, for rotating said spindle to wind a portion of said tie thereon, means engageable with a portion of said buckle and disposed for movement across the rotating axis of said spindle for locating another portion of said buckle between the first and second convolutions in said tie during rotation of said spindle, means effective to retract said spindle in timed relation with the action of said spindle rotating means to release the convolutions of said tie therefrom, means actuated by said shaft for collapsing said convolutions to secure said buckle and means carried by said collapsing means for actuating said buckle portion engaging means.

6. The structure of claim 5 wherein said spindle retracting means is comprised of a rocker arm pivoted intermediate its ends to said common support and having one end pivoted to one end of said spindle, a roller on the opposite end of said rocker arm and a circular cam track carried by said driving wheel with which said roller periodically engages.

7. The structure of claim 5 wherein the means for compressing the convolutions in the tie is comprised of a plunger reciprocable vertically above the end of said spindle about which said tie is wound, a disc on said drive shaft, a connecting rod eccentrically pivoted to said disc at one end and at its opposite end to said plunger and a stationary anvil in alignment with said plunger below the said end of said spindle and against which said convolutions of said tie are compressed by said plunger when said spindle is in retracted position.

8. The structure of claim 5 and ratchet means holding said spindle against rotation in a direction opposite its normal direction of rotation under tensional forces exerted on said spindle by the convolutions of said tie.

9. A machine for attaching a buckle to a bagging tie, comprising a rotatable and horizontally reciprocable spindle having means at one end for holding an end of said tie on which said buckle is loosely mounted in juxtaposition to said spindle, a driving shaft having a driving wheel thereon, a common support for said driving shaft and spindle, a pinion on the opposite end of said spindle, a gear segment on said wheel for intermittent engagement with said pinion to rotate said spindle to wind thereon a portion of said tie, means operating in sequence with the rotation of said spindle to engage and drag said buckle into a position whereby a portion thereof will be disposed between convolutions of said tie during rotation of said spindle, means for retracting said spindle following a predetermined number of revolutions thereof to release the convolutions of said tie, a vertically reciprocable plunger, means for reciprocating said plunger from said driving shaft and means onto which the convoluted end of said tie is deposited from said spindle and against which said plunger is moved to flatten said convolutions and secure said buckle.

10. The structure of claim 9 wherein the means for positioning the buckle in relation to the convolutions of said tie is comprised of a first cam plate affixed to said

plunger, a lever pivoted at one end in relation to said common support, a drag bar disposed transverse to the axis of said spindle and pivoted at one end to the opposite end of said lever, a second cam plate, a first roller carried by said lever and engaging said first cam plate and a second roller carried by said drag bar and supported on said second cam plate whereby vertical recipro-

cation of said plunger will effect transverse reciprocation of said drag bar.
